DISPLAY DEVICE

Filed Feb. 28, 1929

UNITED STATES PATENT OFFICE

EDWIN H. CUMMINGS, OF NORTH ATTLEBORO, MASSACHUSETTS

DISPLAY DEVICE

Application filed February 28, 1929. Serial No. 343,514.

This invention relates to a display device and has for its object to provide an easel-like stand for displaying a plurality of different articles in such a manner that these articles 5 cannot be easily stolen.

A further object of the invention is the provision of a display stand exposing a plurality of articles to be sold and so constituted as to contain articles of a like design to those 10 displayed, which articles are not visible and may be stored behind the displayed articles, for supplying the trade.

A still further object of the invention is the provision of a magazine type of display 15 device in which different articles may be displayed and those selected for purchase may be supplied to the customer from the magazine rather than supplied by the article which is on display.

With these and other objects in view, the invention consists of certain novel features 20 of construction, as will be more fully described, and particularly pointed out in the appended claim:

In the accompanying drawings:

Fig. 1 is a face view of the display stand.

Fig. 2 is a perspective view of the back thereof.

Fig. 3 is a sectional view on line 3-3 of 30 Fig. 1.

Fig. 4 is a sectional view on line 4-4 of Fig. 1.

Fig. 5 is a perspective view of one of the boxes used in the pocket of the display device.

Fig. 6 is a sectional view similar to Fig. 4 showing a modified construction of display device.

In displaying jewelry such as chains and the like, it is found desirable to provide a 40 stand which will expose to view many different patterns or colors of the goods such as chains, so that the customer may compare one pattern or color with another to select the one which suits his taste, and it is also 45 desirable to provide a plurality of any one design so that the complete line carried will not be broken or depleted by the sale of any one design selected by the customer, and in order to accomplish these results in a single device, I have formed a front panel with a

55 pocket on the back which will receive a plurality of different boxes superimposed one upon the other and I have provided a transparent shield thru which the top layer of boxes may be viewed for the inspection and 60 selection by a customer; and the following is a detailed description of the present embodiment of this invention illustrating the preferred means by which these advantageous results may be accomplished:

With reference to the drawings, 10 designates the front panel of the device having a tab 11 extending upwardly therefrom for the reception of a name or advertising matter, as desired. On the back of this panel, there 65 is provided a pocket 12 having side walls 13 and 14, a bottom wall 16 and a back wall 15 from which latter extends a leg 17 for supporting the device in an easel-like fashion with the front panel 10 inclined rearwardly. 70 A flexible tie 27 extends from the lower edge of the leg to the back of the pocket to prevent the weight of the device from bending and sliding the leg from the position illustrated.

An opening 18 is formed in the panel 10 75 to expose the contents of the pocket 12 and is bordered by a finishing strip 28 to enhance the appearance of the device and spanning this opening and also forming a front wall for the pocket 12 is a transparent shield 19 80 of a size larger than the opening 18 to extend a substantial distance over the marginal edges of the opening and to be secured in place by a backing 20 of substantially the size and shape of the front panel 12 with a similar 85 opening to register with the opening 18.

Within the pocket 12 are mounted a plurality of boxes 21, each of which is of identical size and shape. The boxes next to the transparent shield 19 have their covers 22 90 placed over the back of the body portion 23 to expose the articles 24 contained therein thru the transparent shield 19, which layer of boxes I have designated as A in Fig. 4.

Behind the front layer of boxes A is a 95 layer of boxes B, each of which is closed by the cover 22 to completely house the contents 24 thereof.

In use, I intend that each box B will contain an article which is a duplicate of the pat- 100

tern of the article in the box A which is in front of it and exposed to view, so that should the customer select the pattern which happens to be in box designated 25 the merchant could supply this pattern by withdrawing the box B designated 26 from the display stand without disturbing the box 25 which is in display position. In this way the customer obtains a box which has been kept closed to protect the article from dust or foreign matter, while it is unnecessary for the merchant to disturb the article which he has in display position.

It will be understood that the length of the pocket is always formed of an even multiple of the width of the boxes used likewise the width of the pocket is an even multiple of the thickness of the boxes used, and while I have shown the pocket of a size to take but two thicknesses of box, it will be readily understood that the pocket may be multiplied in thickness at will to receive any desired number of boxes one behind the other.

In some cases, I may support the front layer A of boxes independently from the rear layer B, either by having the dimensions of the box so formed that the front layer will be tightly squeezed in between the side walls 13 and 14 of the pocket, as I have illustrated in Fig. 4, or by forming a web 26 secured to the side walls 13 and 14 between the layer A and the layer B.

It will be understood that the pocket 12 is accessible only thru the opening in the top and as the device appears in display position upon the counter the manner in which the articles displayed may be removed is concealed owing to the transparent shield 19 extending across the opening thru which the articles are displayed thus preventing petty thieving and attempted petty thieving.

Further than this the device being of regular formation even though the manner of removing the box were known to the thief, if one box were removed it would be so readily apparent to the storekeeper upon inspection that petty thieving of this character would be minimized owing to the quick detection thereof.

The foregoing description is directed solely towards the construction illustrated, but I desire it to be understood that I reserve the privilege of resorting to all the mechanical changes to which the device is susceptible, the invention being defined and limited only by the terms of the appended claim.

I claim:

A display and vending device for the purpose indicated comprising a front panel having a display opening therein, a backing member substantially the size and shape of the front panel having a display opening therein substantially the size and shape of

said opening in the front panel, a transparent panel secured between said front panel and said backing member, a chamber having rear, side and bottom walls and flanges extending from said side and bottom walls, ⁷⁰ the size of the chamber corresponding to the display opening, a partition wall in said chamber positioned parallel to the front panel and dividing said rear chamber into a display section and a storage section for containing boxes with articles therein to be sold. ⁷⁵

In testimony whereof I affix my signature.

EDWIN H. CUMMINGS.
